[57] CLAIM

The ornamental design for a container for flowers, plants or the like, as shown and described.

DESCRIPTION

FIG. 1 is a side elevational view of a container for flowers, plants or the like showing my new design;

FIG. 2 is a top plan view thereof;

FIG. 3 is a bottom plan view thereof;

FIG. 4 is a sectional view taken in the direction of the arrows on line 4—4 of FIG. 1.
